[57] **CLAIM**

The ornamental design for a single turn current transformer for use as a current sensor, as shown and described.

DESCRIPTION

FIG. 1 is a top plan view of a single turn current transformer for use as a current sensor showing my new design;

FIG. 2 is a rear elevational view;

FIG. 3 is a front elevational view; and

FIG. 4 is an edge elevational view.

FIG. 1

FIG. 2

FIG. 3

FIG. 4
